UNITED STATES PATENT OFFICE.

HAROLD DANIELSON, OF PASSAIC, NEW JERSEY.

TROUGH FOR DISTRIBUTING CONCRETE.

1,206,515.

Specification of Letters Patent. Patented Nov. 28, 1916.

Application filed August 19, 1915. Serial No. 46,276.

To all whom it may concern:

Be it known that I, HAROLD DANIELSON, a citizen of the United States, and a resident of Passaic, in the county of Passaic and State of New Jersey, have invented a new and Improved Trough for Distributing Concrete, of which the following is a full, clear, and exact description.

This invention relates to distributing or spreading machines and particularly to a machine for distributing concrete after the same has been mixed, and has for an object the provision of an improved arrangement whereby the mixed and wet concrete will be distributed evenly and automatically over any desired space.

Another object in view is to provide a distributing trough for distributing concrete from a mixer, the arrangement being such that the concrete is discharged in a continuous stream and at any point desired within a limited radius.

A still further object in view is to provide a distributing trough for concrete which may be collapsed or reduced in length so as to distribute at a distant point from the source of supply or at any intermediate point without changing the position of the source of supply.

Another object of the invention is to provide a distributing trough with propelling means for forcing in a substantially continuous stream concrete to the discharge point of the trough.

Another object is to provide means for swinging the trough from one position to another by power and for adjusting the trough by power, whereby the concrete forced therethrough may be discharged at any point and to any extent.

In the accompanying drawings:—Figure 1 is a side view of an embodiment of the invention applied to a mixer, certain parts being broken away for better illustrating the invention; Fig. 2 is a detail fragmentary view taken approximately on the line 2—2 of Fig. 1; Fig. 3 is an end view of the trough and associated parts shown in Fig. 1, the same being on an enlarged scale; Fig. 4 is a section through Fig. 1 on line 4—4, the same being on an enlarged scale; Fig. 5 is a fragmentary plan view of one end of the trough and associated parts shown in Fig. 1; Fig. 6 is a fragmentary sectional view through Fig. 1 on line 6—6, the same

being on an enlarged scale; Fig. 7 is a fragmentary side view of the outer end of a slightly modified form of trough and associated parts showing a positive drive for adjusting the collapsing of the trough; Fig. 8 is an end view of the structure shown in Fig. 7.

Referring to the accompanying drawings by numerals, 1 indicates a concrete mixer of any desired construction, said mixer being provided with a suitable framework 2 which forms no part of the present invention. Connected with the framework 2 is a cable or guy rod 3 which also is connected at 4 to the trough 5 for supporting the outer end, 60 the inner end resting on the shaft 6 forming part of the mixer 1. Shaft 6 is adapted to rotate when the mixer 1 is in operation and may be connected with the mechanism associated with trough 5 or said mechanism may 65 loosely rest on the shaft, as desired. The trough 5 extends from the bracket 7 to the frame 8, which frame is supported by the guy rope or rod 3, as clearly shown in Fig. 3. This trough is preferably formed of sheet 70 metal and lined with wood saturated in some mineral oil, as for instance, crude oil, whereby the concrete will not readily stick thereto.

An opening 9 is provided in the bottom of the trough, said opening extending to point 85 10 (Fig. 1). In order that the concrete will not fall through the opening until it has arrived at the desired locality, a plurality of covering members or slides 11, 12 and 13 are provided. It is evident that any desired 90 number of slides could be provided and they could be made of any desired length. The provision of these slides is to allow the concrete to be discharged from the trough 5 at any point between the outer end and point 95 10, the various slides being gradually moved inwardly and telescoped over each other as the concrete is laid. For instance, in starting the operation the parts are in the position shown in Fig. 1, and after a certain 100 amount of the concrete has been discharged from the outer end of the trough, slide 13 is moved gradually inwardly, the concrete being continually discharged. After the slide 13 has been moved in for its full length the stop 14 arranged on the hanger 15 will strike 105 against the hanger 16 on slide 12 and will consequently move slide 12 inwardly as the slide 13 is forced inwardly. The movement of both these slides will continue until the 110

stop 17 strikes the hanger 18 which will move hanger 18 inwardly with the remaining slides. When all of the slides have been moved inwardly until the end 10 has been exposed, no further movement can be made as this is the limit of the device. The mixer and associated parts must then be moved to the rear and the slides 11, 12 and 13 moved out again to their full extent and the operation repeated. It is to be noted that in laying concrete on a street or other surface of appreciable width, the trough 5 is swung from one side to the other, back and forth, so as to discharge the concrete evenly over the entire surface.

The slide 13 is provided with hanger 15 and with a hanger 15', while slide 12 is provided with hangers 16 and 16', and slide 11 is provided with hangers 18 and 18'. These hangers are provided with antifriction rollers 19, as shown in Fig. 3, which rollers are mounted upon a plurality of supporting angle irons 20. It will be observed that the hangers 15 and 15' are spaced farther from the trough than the hangers 16 and 16', while these last mentioned hangers are spaced farther from the trough 5 than the hangers 18 and 18'. This will allow the outer slides and hangers to telescope over the inner hangers. The width of the slides 11, 12 and 13 may be varied as circumstances may demand, and, consequently, the opening 9 may be of any desired width. After the slides have all been telescoped and it is desired to move the same outwardly to the position shown in Fig. 1, slide 13 is pulled outwardly and as it moves the hook-shaped stop 21 strikes against the hanger 16 and pulls the same outwardly, and after this hanger has been moved for its full length the same will move the hook-shaped stop 22 connected with hanger 16', which hook-shaped stop will engage the hanger 18 and move the inner slide 11 outwardly. It will thus be seen that the slide 13 is the only slide that need be operated directly as the other slides operate from this slide. This slide may be operated manually as arranged in Fig. 1, or may be connected with power means for operating the same, as shown in Fig. 7 and hereinafter fully described. Also, the trough 5 and associated parts may be swung manually or may be swung by power, as hereinafter described.

Arranged in trough 5 is a screw 23 which is supported by suitable bearing members arranged on the frame 8, frame 8' and bracket 7'. The shaft 24 forming part of the screw 23 extends through the frame 8 at the outer end of the trough 5 and has a sprocket wheel 25 rigidly secured thereto. A chain 26 (Fig. 3) passes over sprocket wheel 25 and also a sprocket wheel 27 rigidly secured to shaft 28. Shaft 28 is journaled in the upper part of the frame 8 and

also is journaled in a bearing 29. The inner end of the shaft 28 near bearing 29 has secured thereto a gear wheel 30 which meshes with gear wheel 31 connected to and operated by a motor 32 of any desired construction, as for instance, an internal combustion engine. As motor 32 operates the power will be transmitted through the structure just described and screw 23 operated. A beveled gear 33 is rigidly secured to shaft 24 near bracket 7', said gear meshing with a beveled gear 34, which beveled gear has a sleeve 35 rigidly secured thereto, said sleeve being preferably part of another beveled gear 36 meshing with a power beveled gear 37. When the engine 32 is operating the power beveled gear 37 is loosely mounted upon the shaft 6. However, a small beveled gear 38 meshes with the power beveled gear 37 and operates shaft 39 to which the friction wheel 40 is secured. The bracket 41 which supports shaft 39 also supports a shaft 42 which has splined thereon beveled friction wheels 43 and 44, said beveled friction wheels being connected by a sleeve 45.

When the parts are in the position shown in Fig. 1 shaft 42 will be driven in one direction, while if they were moved to the opposite extreme by the controlling lever 46 shaft 42 would be rotated in the opposite direction. Shaft 42 carries a pinion 47 at one end which meshes with a gear ring 48, as shown in Fig. 5, which gear ring is held in place by guides 49 and 50. The gear ring 48 continually meshes with a pinion 51 rigidly secured to arms 52, which arms are preferably formed integrally with the bearing plate 53, said bearing plate being also cast integral with the bracket 7 and bracket 7'. The bracket 7 is bifurcated so that the trough 5 may rest therein and may be secured thereto in any desired manner, as for instance, screws or bolts.

By the construction and arrangement just described, when lever 46 is operated, as shown in Fig. 1, so that wheel 43 will press against wheel 40, power will be transmitted to shaft 42 and from thence through the mechanism just described to the bearing plate 53 and from thence to bracket 7, from which it is transmitted to the trough 5 so as to swing the trough in one direction. The speed of swinging movement is regulated by the pressure brought to bear on the wheel 43. When it is desired to swing the trough in the opposite direction lever 43 is moved in the opposite direction so as to cause wheel 44 to engage the wheel 40. In case the engine 32 is not used the power beveled gear 37 is keyed to shaft 6 whereby power from shaft 6 will be transmitted to the parts just described for rotating the screw 23 and also for providing rotary movement for wheel 40 so that the trough

may be swung back and forth as desired. The trough 5 is preferably open for the full length at the top while the inner end 5' is closed so that the concrete will move 5 only in one direction. In order to better direct the concrete which is discharged from the mixer 1 a hopper 54 is provided which may be of any desired width, as shown in Fig. 6, for directing the concrete to the 10 trough.

In the construction shown in Fig. 1 the various slides 11, 12 and 13 are moved manually back and forth, but as heretofore mentioned, these slides may be moved by 15 power, if desired, from the inner end of the trough. As shown in Fig. 7, means are presented which will move the various slides in and out as desired, such movement being automatically produced, or produced man- 20 ually if desired. In producing a structure of this kind the sprocket wheel 27 is connected with a shaft 55 journaled in the upper part of the frame 8'. Shaft 55 carries a gear 56 and pinion 57, pinion 57 continu- 25 ally meshing with an idler 58, said idler being designed to mesh with gear 59 when moved to the position shown in Fig. 7. Whenever desired gear 59 may be moved into mesh with gear 56 by operating lever 30 60, the gears sliding on the shaft 61. Shaft 61 carries a beveled gear 62 which meshes with beveled gear 63 rigidly secured to shaft 64. Shaft 64 carries a pair of sprocket wheels 65, as shown in Fig. 8, whereby a 35 pair of chains 66 may be operated. The chains 66 are connected to the opposite hangers 15 by any suitable means, as for instance, U-bolts 67. By this construction and arrangement it will be seen that when 40 the screw 23 is operating power will be transmitted to the chains 66 for gradually moving the outer slide 13 inwardly and eventually all of the sides inwardly. By operating lever 60 the direction of move- 45 ment of the chains 66 may be changed so that the slides will move outwardly.

It will be observed that gear wheel 56 is larger than gear wheel 57 so that the outward movement will be faster than the in- 50 ward movement in proportion to the speed of the screw 23.

What I claim is:—

1. In a concrete spreading machine, a concrete guiding trough having an open bottom, a plurality of sections slidably mounted on said trough and normally covering said open bottom, and means for moving said sections successively for varying the effective length of the trough, whereby concrete passing through the trough may be discharged at any point between the ends thereof.

2. In a distributing mechanism for concrete, a trough for guiding the concrete mixture, means arranged in the trough for pro-

pelling the mixture toward the outer end, a plurality of telescoping members arranged on the trough for varying the effective length of the trough whereby the concrete may be discharged at any desired point along 70 the trough, and means arranged at the inner end of the trough for swinging the trough horizontally while the concrete is being forced therethrough.

3. In a concrete distributing device, a 75 trough for receiving concrete at one end, means for transporting concrete along said trough toward the outer end, said trough being open at the bottom, a plurality of telescoping members for closing said opening, 80 said telescoping members being adapted to be moved successively from beneath the trough so as to shorten the effective length of the trough, whereby said concrete may be discharged at any desired point between the 85 ends of the trough, and means for supporting said trough so that the same may be swung in a substantially horizontal plane.

4. In a distributing trough for concrete, a pivotally mounted body formed with an 90 open bottom extending from the outer end to near the inner end, means for pivotally supporting the inner end, covering slides for the opening in the bottom of said body, means for suspending for holding in position said slides, said supports being formed so as to allow the slides to telescope over each other as the slides are moved toward the inner end of the body, whereby the effective length of the body is varied, and a screw ar- 95 ranged in said body for propelling concrete 100 toward the outer end of said body.

5. In a concrete spreading device, a pivotally mounted trough, a plurality of slides arranged adjacent the bottom of said trough, 105 said trough being open at the bottom so that said slides form a bottom therefor, means for moving said slides inwardly so as to affect the operative length of the trough, a screw arranged in the trough for feeding 110 concrete outwardly therethrough, and a power member arranged on the trough and connected with said screw for rotating the same.

6. In a device for distributing concrete, a 115 pivotally mounted trough adapted to receive concrete at its pivotal end, a plurality of telescoping trough members associated with said trough, said trough being formed open at the bottom so that as the trough members 120 are telescoped toward the pivotal end of the trough the effective length of the trough will be lessened, a screw arranged in said trough for forcing concrete from the pivotal end toward the outer end, and means for swinging said trough together with said screw in a horizontal plane.

7. In a concrete distributing device, a pivotally mounted chute adapted to swing in a horizontal plane, said chute having an open- 130

ing in the bottom thereof extending from the outer end to near the inner end, means arranged in the trough for forcing concrete along the trough toward the outer end, covering slides or sections for covering the opening in the bottom of said trough, a plurality of tracks arranged on said trough, and hangers connected with said slides and overlapping said tracks whereby the slides 10 are supported by said trough, said hangers being of different length so that the slides may telescope over each other as the same are collapsed toward the pivotal end of the trough.

15 8. In a concrete distributing device of the character described, a distributing trough, a screw arranged in said trough, a power member for driving said screw, and means connected with said screw for swinging said trough in a horizontal plane.

20 9. In a concrete distributing device of the character described, a swinging trough formed into parts so that the effective length of the trough may be varied, a screw 25 arranged in said trough for propelling concrete along said trough, a power shaft, means for connecting said power shaft with said screw for driving the same, a friction drive connected with the means for driving said screw, means for connecting said friction drive with said trough for swinging the same in a horizontal plane, and manually actuated means for controlling the action of said friction drive, whereby the trough may

be swung in either direction and at any desired speed. 35

10. In a concrete spreading machine of the character described, a trough for distributing concrete, said trough being formed with telescoping means for varying the effective length of the trough, a member moving longitudinally of the trough connected with the means for varying the effective length of the trough so as to actuate the same, means arranged in the trough for propelling concrete along the trough, and connections between said propelling means and the longitudinally movable member whereby power is communicated through said propelling means to said longitudinally movable member. 40 45

11. In a concrete spreading machine of the character described, a distributing trough formed with collapsing sections, a screw arranged in said trough for propelling concrete along the trough, means for operating said screw, a traveling member for operating said telescoping sections whereby the effective length of the trough is varied, and means for connecting the screw and said traveling member. 50 55

In testimony whereof I have signed my name to this specification in the presence of two subscribing witnesses.

HAROLD DANIELSON.
